UNITED STATES PATENT OFFICE.

CLAUDE R. DODGE, OF ROCKFORD, ILLINOIS.

TAG.

1,108,835.

Specification of Letters Patent. Patented Aug. 25, 1914.

Application filed August 23, 1912. Serial No. 716,694.

To all whom it may concern:

Be it known that I, CLAUDE R. DODGE, a citizen of the United States, residing at Rockford, in the county of Winnebago and State of Illinois, have invented new and useful Improvements in Tags, of which the following is a specification.

The invention relates to tapes, and more particularly to the class of tag tapes.

10 The primary object of the invention is the provision of a tag tape wherein a single tag may be separated therefrom and readily fastened upon an article to be laundered so that such article can be readily and conveniently identified and also the said tag can be readily removed without injury to the fabric forming the article.

Another object of the invention is the provision of a tag tape which can be readily used in an automatic tagging machine, so that single tags may be readily fastened to articles of wearing apparel or the like during the successive operation of the tagging machine and in this manner avoiding the necessity of hand tagging of the articles, each tag being readily removable from the article without damaging the latter or the fingers of a person while in the act of removing such tag.

30 A further object of the invention is the provision of a tag tape wherein the tags thereof are arranged in rows and the locking teeth are so protected that on the rolling of the tape the locking teeth will not interfere with the unrolling of the said tape when placed within a tagging machine when the latter is in operation for tagging articles.

40 A still further object of the invention is the provision of a tagging tape wherein each tag proper thereof is enveloped or covered with a fabric so that when each tag is placed upon an article, the latter will be protected from the metal body of the tag thereby avoiding damage to the article.

50 A still further object of the invention is the provision of a tag tape which is simple in construction, permitting each tag thereof to be readily separated from an adjacent tag as well as permitting the tag to be readily and quickly applied to an article and also which may be manufactured at a minimum expense.

With these and other objects in view the 55 invention consists in the construction, combination and arrangement of parts as will

be hereinafter more fully described, illustrated in the accompanying drawings, and pointed out in the claims hereunto appended.

In the drawings: Figure 1 is a fragmentary plan view of a tag tape with the fabric covering removed. Fig. 2 is a similar view showing the fabric covering fastened thereon. Fig. 3 is an enlarged sectional view on the line 3—3 of Fig. 1. Fig. 4 is an enlarged sectional view on the line 4—4 of Fig. 2. Fig. 5 is a vertical transverse sectional view through one of the tags when in folded position. Fig. 6 is a similar view showing the tag secured to a piece of material.

Similar reference characters indicate corresponding parts throughout the several views in the drawings.

Referring to the drawings by numerals 75 the tag tape comprises a flexible strip A, preferably constructed from bendable metal, and is formed at predetermined intervals with opposite alining slots 10, which open through opposite longitudinal edges of the 80 strip A, and have their inner closed ends terminating spaced from each other at medial line throughout the extent of the said strip, the said slots being disposed transversely in the strip and form therebetween tag sections 85 11, and narrow connecting portions 12 joining the said sections, whereby on the severing of the connection 12, the tag sections 11 can be separated from each other for the mounting of the same upon articles to be 90 laundered in a manner presently described. Cut and struck up from the tag sections 11 on opposite sides of this medial line are bendable teeth or spurs 13, which are adapted to be passed through a fabric covering 14, 95 the latter being folded over the longitudinal edges and opposite sides of the strip A, so that the longitudinal edges of the covering 14 will be brought in close relation to each other, and engaged by the teeth or spurs 13 100 which are bent inwardly and downwardly for the fastening of the covering 14 in taut condition upon the strip. The covering 14 is provided with kerfs 15 alining with the slots 10 in the strip A, the said kerfs 15 being 105 of uniform size with respect to the said slots as shown in Fig. 2 of the drawing, so that the connecting portions 12 may be severed without tearing away the covering 14 when separating the tag sections from each other. 110 It is of course understood that the strip A after being covered as heretofore described

is rolled and placed upon a reel in a tagging machine, whereby the tagging sections 11 can be bent and fastened to an article in a manner presently described..

5 Cut from the tag sections 11 near diametrically opposite corners are bendable nibs or tongues 16 which latter are normally slightly outwardly bulged at 17 as shown in Figs. 1, 3 and 4 of the drawings, 10 so that when each tag section 11 has been separated from an adjacent tag section and the same has been acted upon by the tagging machine for the bending thereof into substantially U-shape, the nibs or tongues 15 16 can be readily instruck to the position shown in Fig. 6 of the drawings by the tagging machine for the fastening of the tag section on an article to be laundried.

When it is desired to remove the tag section after being fastened to the article 18 as shown in Fig. 6 by the tagging machine, it is only necessary to spread the end portions apart for separating the same from the piece of material 18, and thereby freeing the tag section for its removal from the piece of material.

From the foregoing description, taken in connection with the accompanying drawings, it is thought that the construction, combination and arrangement of parts will be clearly understood, and therefore, a more extended explanation has been omitted.

What is claimed is:—

1. A tag comprising a flat body having inner and outer series of spurs struck therefrom, and a covering piece disposed over

one face of the body and having opposite ends bent about the end edges of the latter on to the opposite face of said body and engaged with the inner series of spurs, the 40 said outer series of spurs being outwardly bowed and normally concealed between the stretches of the covering piece on both sides of the body and having their free ends directed toward each other, whereby on inwardly depressing the said outer series of spurs they will pass through the covering piece at one side of the body for biting engagement in an article for the fastening of a tag thereto. 45

2. A tag comprising a blank, spurs struck from said blank near opposite ends thereof and projected intermediate their ends beyond one face of the blank with the free ends of the spurs normally flush with the 50 surfaces of the said blank, and a covering for the blank completely inclosing the said blank and spurs.

3. A tag comprising a blank, spurs struck from said blank and projecting intermediate 60 their ends beyond one face of the blank with the free ends of each spur normally flush with the faces of the blank, and a covering for the blank completely inclosing the same and the spurs.

In testimony whereof I affix my signature in presence of witnesses.

CLAUDE R. DODGE.
